UNITED STATES PATENT OFFICE.

PAUL S. LUTTRELL, OF OAKLAND, CALIFORNIA, ASSIGNOR TO REMINDER CLOCK CO., OF OAKLAND, CALIFORNIA, A CORPORATION OF CALIFORNIA.

TIMING DEVICE.

1,213,516.

Specification of Letters Patent. Patented Jan. 23, 1917.

Application filed June 30, 1915. Serial No. 37,355.

To all whom it may concern:

Be it known that I, PAUL S. LUTTRELL, a citizen of the United States, residing at Oakland, in the county of Alameda and State of California, have invented new and useful Improvements in Timing Devices, of which the following is a specification.

This invention relates to a timing device, and particularly to what may be known as interval clocks or clocks that are adapted to be set so as to run for a predetermined period of time and at the end of that period stop running and at the same time sound an alarm, giving notice that the predetermined interval of time has elapsed.

The object of the present invention is to improve the construction of the device of the character described to make it fool-proof, simple and substantial and cheap to manufacture.

The invention consists of the parts and the construction and combination of parts as hereinafter more fully described and claimed, having reference to the accompanying drawings, in which—

Figure 1 is a front view of the timing device. Fig. 2 is a section on line 2—2, Fig. 3. Fig. 3 is a cross section of the casing, showing the clock mechanism in elevation. Fig. 4 is an enlarged section of the winding shafts, with connected gears and operating key.

Referring in detail to the accompanying drawings, A indicates the bearing plates, between which the clock mechanism is mounted; B an inclosing sheet-metal casing of suitable shape and construction; 2 a graduated dial plate; and 3 the indicator hand. The clock mechanism proper is divided into two groups, one group of gears operating an alarm device and the other gear train operating the indicator hand and a trip mechanism for the alarm. The alarm and indicator hand mechanism are set and wound by means of two winding shafts 4 and 5 which are adapted to turn in unison and independent of each other through means of a knurled winding key 6 and attached ratchet pawls indicated at 7, 8 and 9. This is accomplished in the following manner: The winding key prong is loosely mounted on the outer end of shaft 4, in front of the dial plate 2, and the hub section of same is provided with an upwardly projecting pin 10 which is adapted to engage with the pawl 7,

which in turn is mounted on a disk 11 secured to shaft 4, as indicated at 12.

Mounted on the opposite side of the disk is the second pawl 8 which is engageable with a recess 13 formed in the face of a sleeve 14, loosely mounted exteriorly of the winding shaft 5. Secured to the inner end of shaft 4 is a second disk 15, upon which pawl 9 is carried, and loosely mounted on the hub 16 of disk 15 is a spur gear 17 which is adapted to turn in unison with shaft 4, disk 15 and pawl 9, when the pawl is moved into engagement with a pin 18 secured in the hub of gear 17.

Intermeshing with gear 17 is a second spur gear 19 which is secured upon a winding shaft 20, to which one end of the alarm spring 21 is secured, and driven by said shaft is a star gear 22 which operates a knocker arm 23, the outer end of which engages the bell 24 to sound an alarm. The gear train employed in connection with the bell alarm here shown is of standard construction, such as used in ordinary alarm clocks, the only difference being the provision of the spur gears 17 and 19 by which the spring is wound.

The other part of the clock mechanism employed for turning the indicator arm and also for operating the trip for the alarm is actuated from the second winding shaft 5 through means of a ratchet gear 25 which engages a double ratchet pawl 26 mounted on an arm 27 which is secured upon the loosely mounted sleeve 14. The main clock spring 28 is secured at its inner end to the sleeve 14 and at its outer end to a post 29 secured in the main frame plate A. The shaft 5 and main clock spring 28 when wound will return to the unwound position in the usual manner; the return movement being controlled by the usual form of escapement, generally indicated at 30, which is driven from a gear 31 secured on shaft 5.

In operation, when it is desired to set the timing device, it is accomplished by turning the main exterior winding key 6 in the direction of arrow a. The pin 10 on the hub of the key will thus engage pawl 7, causing it to turn disk 11, with connected shaft 4, in the same direction. Movement is in this manner immediately transmitted to turn disk 15, with attached pawl 9, causing it to engage pin 18 on the spur gear 17, thereby operating the connected gear 19 and causing

the alarm spring to be wound or set. The position of the pawls 7 and 9 is such that shaft 4 will be turned half a revolution before pawl 8 will drop into recess 13, formed on the sleeve 14; in other words, the alarm spring will be wound and set before pawl 8 engages with shoulder 13 and any movement is transmitted to turn the exterior winding shaft 5. Further turning movement of the key 6, after pawl 8 has been moved into engagement with recess 13, will cause sleeve 14, with connected arm 27 to move in the same direction, causing the main cock spring 28 to become wound and the dial hand 3 to be moved as this is secured on the sleeve 14; the key being turned until the desired time is indicated by the hand. The key is then released permitting the clock mechanism to operate and return the hand to zero position, causing the clock to stop and at the same time an alarm to be given. The return movement or speed of the indicator hand 3 is limited by the turning movement of shaft 5 and the escapement 30; the indicator hand turning in unison with sleeve 14 and arm 27 through means of the double pawl 26 which engages with the teeth in ratchet wheel 25 secured upon shaft 5.

The return movement of shaft 5 caused by the driving action of the main clock spring 28 through arm 27, pawls 26 and ratchet gear 25, which is limited by the escapement movement 30, will finally bring the indicator arm 3 back to zero position. Instantaneously with the arrival of the hand 3 at this point the lower end 33 of arm 27 engages with a bell-crank 34 tripping this and releasing the alarm mechanism to permit the knocker arm to operate. The alarm is thus given instantly with the arrival of the indicator hand at zero position, giving the desired warning.

The provision of the loosely mounted winding key 6 makes the structure as a whole practically fool-proof as the key can be turned as often as desired in the wrong direction without affecting the connected mechanism in any manner. The turning of the key in the right direction brings the connected winding shafts 4 and 5 into operation one after the other. As previously described, the inner shaft 4 is first turned to wind the alarm before the indicator hand is turned by means of the sleeve 14. The winding of the alarm in this manner is accomplished before the indicator hand is moved and the winding of the alarm spring is thus independent of the indicator arm, or, in other words, the movement of the indicator arm will not effect the successful operation of the alarm as the alarm spring is already sufficiently wound before the hand is moved. The hand can in this manner be moved a very slight distance or a greater distance, as the case may be.

The provision of the double pawl 26, which engages the ratchet gear 25, of standard construction, having sixty teeth permits the hand to be set at points on the dial indicating minutes or half minutes as one pawl is a little shorter than the other; the spacing between the two pawls being half the distance between two teeth on the gear, thus permitting the arm 27 and hand 3 to be set at minutes and half minute graduations.

While the dial here shown is graduated into minutes and half minutes, running from zero to sixty minutes or one hour, I wish it understood that any desired time 80 graduations may be provided and that by the employment of a different escapement the speed of the hand may accordingly be regulated for second readings, or otherwise. A timing device constructed as here shown 85 is neat in appearance, simple and substantial in construction and absolutely fool-proof as turning movement of the key in the wrong direction will not effect the operating mechanism in any manner.

The device may be used for many purposes, for instance, as a timing device in connection with culinary purposes of all kinds, both in the home and factory. It may also be used to great advantage in connection 95 with photographic work, such as printing and developing time exposures, etc. It has also been found useful in connection with many of the manufacturing arts where the element of time enters as a necessary factor 100 and also as a timer in telephone offices where long distance calls are controlled by time.

The materials and finish of the several parts of the timing device are such as the experience and judgment of the manufacturer may dictate.

I wish it understood that various changes in form, proportions and minor details of construction may be resorted to within the scope of the appended claims and that I do not wish to limit myself to the specific design and construction here shown.

Having thus described my invention, what I claim and desire to secure by Letters Patent is—

1. In a timing device, an alarm mechanism, a connected spring-actuated driving mechanism, an indicator hand, a connected spring-actuated driving mechanism, a pair of winding shafts, one connected with the alarm driving mechanism and the other with the indicator driving mechanism, means for turning the alarm winding shaft, and means on the alarm winding shaft for turning the other winding shaft.

2. In a timing device, an alarm mechanism, a connected spring-actuated driving mechanism, an indicator hand, a connected spring-actuated driving mechanism, a pair of winding shafts one interior of the other,

one connected with the alarm driving mechanism and the other with the indicator driving mechanism, and means for turning said shafts independently of each other and in 5 unison with each other.

3. In a timing device, an alarm mechanism, a connected spring-actuated driving mechanism, an indicator hand, a connected spring-actuated driving mechanism, a pair 10 of winding shafts, one connected with the alarm driving mechanism and the other with the indicator driving mechanism, a winding key loosely mounted on the alarm winding shaft, means for automatically locking the 15 shaft to turn in unison with the key, and means for automatically coupling the indicator hand winding shaft to turn in unison with the alarm winding shaft and winding key.

20 4. In a timing device, an alarm mechanism, a connected spring-actuated driving mechanism, an indicator hand, a connected spring-actuated driving mechanism, a winding shaft connected with the alarm driving 25 mechanism, a winding key loosely mounted on said shaft, a ratchet member secured on the shaft, a pin on the winding key engageable with said ratchet member to turn the ratchet and shaft, a tubular shaft exteriorly 30 of the alarm winding shaft connected with the indicator hand driving mechanism, and means for automatically coupling said shaft to turn in unison with the winding key and alarm winding shaft.

35 5. In a timing device, an alarm mechanism, a connected spring-actuated driving mechanism, an indicator hand, a connected spring-actuated driving mechanism, a winding shaft connected with the alarm driving 40 mechanism, a winding key loosely mounted on said shaft, a ratchet member secured on the shaft, a pin on the winding key engageable with said ratchet member to turn the ratchet and shaft, a tubular shaft exteriorly 45 of the alarm winding shaft connected with the indicator hand driving mechanism, and a second ratchet member secured to the first named winding shaft engageable with a member on the tubular winding shaft to 50 turn said shaft, a trip mechanism connected with the alarm mechanism, and means on the tubular shaft for releasing the trip.

55 6. In a timing device, an alarm mechanism, a connected spring-actuated driving mechanism, an indicator hand, a connected spring-actuated driving mechanism, a pair 60 of winding shafts, one connected with the alarm driving mechanism and the other with the indicator driving mechanism, means for turning the alarm winding shaft, means on said shaft for turning the other winding shaft, a trip mechanism connected with the alarm mechanism, and means on the last named shaft for releasing the trip mechanism.

65 7. In a timing device, an alarm mechanism, a connected spring-actuated driving

mechanism, an indicator hand, a connected spring-actuated driving mechanism, a pair of winding shafts, one connected with the alarm driving mechanism and the other with the indicator driving mechanism, a winding key loosely mounted on the alarm winding shaft, means for automatically locking the shaft to turn in unison with the key, means for automatically coupling the indicator hand winding shaft to turn in unison with the alarm winding shaft and winding key, a trip mechanism connected with the alarm mechanism, and means on the indicator hand winding shaft for releasing the trip. 70 75 80

8. In a timing device, an alarm mechanism, a connected spring-actuated driving mechanism, an indicator hand, a connected spring-actuated driving mechanism, a winding shaft connected with the alarm driving 85 mechanism, a winding key loosely mounted on said shaft, a ratchet member secured on the shaft, a pin on the winding key engageable with said ratchet member to turn the ratchet and shaft, a tubular shaft exteriorly 90 of the alarm winding shaft connected with the indicator hand driving mechanism, a second ratchet member secured to the first named winding shaft engageable with a member on the tubular winding shaft to 95 turn said shaft, a trip mechanism connected with the alarm mechanism, and means on the tubular shaft for releasing the trip.

9. The combination with the two winding shafts mounted one interior of the other, 100 of a safety key loosely turnable on the exterior shaft, means for automatically coupling the key to said shaft, and means for automatically coupling said shaft to the interior shaft to cause same to turn in 105 unison.

10. In a timing device, the combination with the alarm winding shaft and the tubular shaft, of a winding key loosely turnable on the alarm winding shaft in one direction, means for automatically coupling the key to the shaft when it is turned in the opposite direction, and means for automatically coupling the tubular shaft to turn in unison with the alarm winding shaft 110 115 after said shaft has been turned a predetermined distance.

11. In a timing device, an alarm mechanism, a connected spring-actuated driving mechanism, an indicator hand, a connected spring-actuated driving mechanism, a pair 120 of winding shafts, one interior of the other, one connected with the alarm driving mechanism and the other with the indicator driving mechanism, means for manually turning the inner shaft and means for automatically connecting the exterior shaft to turn in unison with the inner shaft after the inner shaft has been turned a half revolution. 125 130

12. In a timing device the combination with the inner and outer winding shafts of a ratchet gear secured on the outer shaft, a sleeve turnably mounted on said shaft, an arm secured on the sleeve and a pair of pawls carried by the arm, engageable with the ratchet gear, one of said pawls being longer than the other and one pawl adapted to assume a position intermediate of a pair 10 of teeth on the ratchet gear while the other pawl is in engagement and vice versa.

13. In a timing device, an alarm mechanism, a connected spring-actuated driving mechanism, an indicator hand, a connected 15 spring-actuated driving mechanism, a pair of winding shafts, one interior of the other, one connected with the alarm driving mechanism and the other with the indicator driving mechanism, a key mounted on the 20 inner shaft adapted to turn free on the shaft in one direction, and means for locking the key to turn the shaft when turned in the opposite direction, and means for automatically connecting the exterior shaft to turn 25 in unison with the inner shaft after the inner shaft has been turned a half revolution.

14. In a timing device, the combination with the alarm winding shaft and the tubular shaft, of a winding key loosely turnable on the alarm winding shaft in one direction, means for automatically coupling the key to the shaft when it is turned in the opposite direction, and means for automatically coupling the tubular shaft to turn 30 in unison with the alarm winding shaft after said shaft has been turned a predetermined distance, said means comprising a disk secured on the alarm winding shaft, a pawl carried by the disk, a sleeve turnably 35 mounted on the tubular shaft, a recess in said sleeve with which the pawl is adapted to engage, an arm secured on the sleeve, a pawl on said arm and a ratchet gear secured on the tubular shaft with which 40 said last named pawl is engageable.

In testimony whereof I have hereunto set my hand in the presence of two subscribing witnesses.

PAUL S. LUTTRELL.
